L. P. DICKY

VANITY CASE

Filed April 22, 1922

Fig. 2.

Inventor
Lawrence P. Dickey

T. Bay Lindsey

Sis. Attorney

UNITED STATES PATENT OFFICE.

LAURENCE P. DICKEY, OF MOUNTAIN LAKES, NEW JERSEY.

VANITY CASE.

Application filed April 22, 1922. Serial No. 556,046.

To all whom it may concern:

Be it known that I, LAURENCE P. DICKEY, a citizen of the United States, and a resident of Mountain Lakes, in the county of Morris, State of New Jersey, have invented certain new and useful Improvements in a Vanity Case, of which the following is a specification.

This invention relates generally to a metal vanity case or like receptacle for holding rouge compacts, face powder, powder puffs, or other toilet article.

The object of the invention is to provide a metallic vanity case having various features of novelty and advantage and which is particularly characterized by its simplicity and economy in construction and its neat and pleasing appearance. My invention has for its further object to provide a vanity case of this sort with simple and effective means for securing a decorative cover piece in place in the top of the box, preferably this cover piece being removable so as to give the retailer or user an opportunity to change the decorative effect to suit his or her own taste, and has for its further object to secure the decorative piece in place in the top of the box, in part, by a member having a mirrored surface.

Heretofore, it has been the practice to paste a label on the top of the vanity case to give it an ornamental effect or to designate its origin, but the difficulty with this scheme has been that, after the vanity case has left the manufacturers' hands, the label in some instances would become displaced and in others would become scratched and torn, and in no instance was there any opportunity to renew the label when it did become worn or for the purpose of suiting the whim of the retailer or user. Also, it has been proposed to stamp, by means of a die or the like, the ordinary cover of a metal vanity case in order to give it the desired design, but owing to the gauge of the metal of which the case is constructed, it has been impossible to obtain as fine and distinct an effect as is desired.

In accordance with the present invention, I provide a vanity case having, for instance, its top in the form of an annulus having a peripheral flange depending downwardly therefrom and adapted to telescope the lower portion of the box, a disk adapted to fit in the top, and a cover piece adapted to be held

in place between the disk and the flange, suitable means being provided for removably holding the disk in place and preferably the inner surface of the disk has a mirrored surface for the convenience of the user. The cover piece, which may be of any design or effect and which may be of any suitable material, provides a cover which gives a very neat and pleasing appearance. 65

In the accompanying drawing:—

Fig. 1 is a perspective view of a vanity case with the lid or top thrown back;

Fig. 2 is a sectional view therethrough;

Fig. 2^a is a detail view showing a portion 70 of Fig. 2 on an enlarged scale;

Fig. 3 is a perspective view of the parts of the top.

Referring to the drawing in detail, *a* denotes the body portion of the box and *b* the 75 cover hinged thereto as at *c*. The cover *b* has its top wall cut away as at 10 thus providing a relatively narrow annulus 11 provided with a peripheral flange 12. Fitted within the said flange 12 is a disk 13 the inner face thereof, preferably, being mirrored. In the present instance, this disk is shown as being in the form of a glass mirror. The decorative cover or label 14 which may be of cloth, paper, or other suitable material bearing the 85 desired design is located intermediate the inner surface of the annulus and the top of the disk 13. This cover piece is generally circular and is greater in diameter than the opening in the annulus 11 so that the edge 90 of the cover piece 14 is covered by the annulus.

In the embodiment shown in Figs. 1 to 3, the mirrored disk 13 and the cover piece 14 are secured in place by a bezel 15 of substantially the same diameter as the internal diameter of the cylindrical portion 12 of the top so as to have a close frictional fit therein. It will be seen that the edge of the cover piece is positioned between the 100 disk 13 and the annulus 11 and that the parts are securely held in place by the ring 15. The assembling and disassembling of the parts may be very readily and quickly brought about, making it very easy for any 105 one who so desires to renew the cover piece 14 or change it for a design which better suits his taste.

As clearly shown in Fig. 2^a, the cover piece 14 may if desired be formed with a 110 raised or struck up portion 16 of such shape

- that it completely fills the cut away portion 10 of the cover *b* and prevents the cover piece from shifting laterally although obviously it can be as readily used flat if the inner edge of the annulus is not objectionable. The remaining portion of the latter forms a flange 17 which is adapted to lie behind the annulus 11 forming part of the cover *b* and prevent the cover piece from being pushed outwardly. The height of the struck up portion 16 is preferably made equal to the thickness of the material of which the vanity case is constructed, so as to avoid forming a ridge between it and the edge of the annulus 11. With this arrangement, the top of the vanity case, particularly if the label were given a brass finish, would appear, to the casual observer, to be made of an integral sheet of brass suitably embossed.
- 20 A vanity case may, of course, be of other than circular shape and the cover instead of being hinged may be of the slip type or otherwise. The cover piece in either embodiment may or may not have, as desired, its edge extending over the edge of the disk. The edge of the cover piece may be pasted or otherwise attached to the disk and frictionally held between the top of the disk and the annulus 11 or between the edge of the disk and the peripheral flange 12 or both, as desired.
- 25 It is, of course, obvious that the invention is susceptible of various other modifications and changes which are within the spirit of the invention without departing from the scope of the following claims, it being understood that the present disclosure of my invention is by way of illustration only and it is not to be taken as restrictive of my conception.
- 30 I claim as my invention:—
1. In a vanity case comprising a mirror and means to carry cosmetics, the combination of an annular cover and a removable label therefor, the latter comprising a struck up portion shaped to fill the center of the annulus and a circumferential flange for firmly seating said label.
- 35 2. A vanity case having a top formed of an annulus provided with a peripheral flange, a disk fitting in said flange and having a mirror on its inner face, and a removable cover piece over said disk and interposed between the disk and annulus.
- 40 3. A metal vanity case having a top formed of an annulus provided with a peripheral flange, a mirror within said flange, a cover piece over the back of said mirror with its edges interposed between said mirror and annulus, and a bezel in said flange for holding said mirror in place.
- 45 4. A vanity case having a top formed of an annulus provided with a peripheral flange, a mirror closely fitting within said flange, a cover piece over the back of said mirror and having its edges interposed and clamped between the said mirror and flange.
- 50 5. In a vanity case containing a mirror and means to carry cosmetics, the combination of a cover provided with an opening through the outer wall thereof and an insert secured in said cover and exposed through said opening and means for firmly seating and retaining the insert in position.
- 55 6. In a vanity case containing a mirror and means to carry cosmetics, the combination of a cover provided with an opening through the outer wall thereof and an insert secured in said cover and exposed through said opening and frictional means for firmly seating and retaining the insert in position.
- 60 7. In a vanity case containing a mirror and means to carry cosmetics, the combination of a cover provided with an opening through the outer wall thereof and an insert removably seated in the cover and exposed through the said opening.
- 65 8. In a vanity case containing a mirror and means to carry cosmetics, the combination of a cover provided with an opening through the outer wall thereof and an insert removably and frictionally seated in the cover and exposed through the said opening.
- 70 9. In a vanity case containing a mirror and means to carry cosmetics, a top formed with an annulus provided with a peripheral downwardly extending flange, thus providing an enlarged opening through the outer wall of the top, a removable disk within the said flange and closing said opening, and a removable cover piece intermediate said disk and the annulus.
- 75 10. In a vanity case containing a mirror and means to carry cosmetics, a top formed of an annulus provided with a peripheral flange, a disk fitted in said flange, a cover piece over said disk and interposed between said annulus and disk, and means for frictionally holding said disk in position.
- 80 11. In a vanity box containing a mirror and means to carry cosmetics, an opening through the outer wall of said box and an insert supported in the case and exposed through the opening.

LAURENCE P. DICKEY.
